BUILDING STRUCTURE

Frederick M. Venzie, Philadelphia, Pa.

Application May 17, 1929. Serial No. 363,894

1 Claim. (Cl. 72—118)

This invention, stated in its broadest terms, relates to a building structure and has more especial relation to a wall, partition, and ceiling structure in which so-called plaster boards of water-proofed type are employed.

One object of the present invention may be said to reside in the provision of water-proofed plaster boards of the type which have a covering of paper which paper upon the rear face of the plaster board I treat with a water-proofing composition and thereafter apply a coating of asphaltum paint to render the entire structure non-porous to resist moisture, dampness, and the like.

Another object of the present invention is to provide a plaster board of the character stated in which I apply to the paper upon the front face of the plaster board a coating of fire resisting material which renders the paper porous in character.

20 A further object of the present invention may be said to reside in the provision of means whereby unskilled labor may more rapidly and efficiently erect ceilings, walls, and partitions of plaster boards, thereby to reduce building costs.

25 A further object of the present invention is to provide a structure of the character stated which not only is entirely constructed of water-proofing and fire-proofing material but is sound proof, very strong, and very cheap to erect.

30 A still further object of the present invention is to provide novel forms of metallic clips for supporting adjacent ends of the plaster boards.

Other and further objects of the present invention reside in the provision of a general arrangement, combination and connection of parts for attaining the results sought by the foregoing objects.

The invention consists of the novel construction hereinafter described and finally claimed.

40 The nature, characteristic features and scope of the invention will be more fully understood from the following description taken in connection with the accompanying drawings forming part hereof, and in which:

Fig. 1 is a view partly in section and partly in elevation illustrating a ceiling and wall structure embodying the invention.

Fig. 2 is a fragmentary view in elevation showing the front faces of the plaster boards.

Fig. 3 is a view in perspective of the clip as used at the floor and ceiling of my building structure.

Fig. 4 is a view in perspective of a clip as used 55 between adjacent plaster boards.

Fig. 5 is a fragmentary view in section illustrating the plaster board construction.

Fig. 6 is a view in elevation illustrating a detail of a modified construction.

Fig. 7 is a view in perspective of one of the 60 members shown in Figs. 2 and 6; and

Fig. 8 is a view in perspective of another of the members shown in Figs. 2 and 6.

For the purpose of illustrating my invention I have shown in the accompanying drawings one 65 form thereof which is at present preferred by me, since the same has been found in practice to give satisfactory and reliable results, although it is to be understood that the various instrumentalities of which my invention consists can be variously 70 arranged and organized and that my invention is not limited to the precise arrangement and organization of the instrumentalities as shown and described herein.

In the novel ceiling, wall, and partition structure of the present invention I make use of conventional plaster board of the type which is comprised of a water proofing plaster composition having a covering of paper. According to the present invention I first treat the paper covering 80 upon the back of a plaster board with a suitable composition having water-proofing characteristics and thereafter apply to said water-proofed portion of the paper a coating of asphaltum paint. The asphaltum paint may be applied in either a heated or cooled condition. This treatment renders the rear face of the plaster board non-porous to guard against the penetration of moisture, dampness and the like.

To the front face of the paper covering the plaster board I apply a fire resisting composition which renders porous the front face of the paper covering the plaster board. Not only is the plaster board thereby rendered water-proof and fire-proof in character, but it also provides a very efficient, 95 strong, and sound resisting plaster board.

In the drawings, and referring to Fig. 1, the reference numeral 1 designates a conventional plaster board composed of a plaster composition possessing water-proofing characteristics. The 100 composition 2 is provided with a covering of paper 3. The paper covering the rear portion of the plaster board I treat with any suitable material to render the same water-proofing in character and thereafter apply a coating 4 of asphaltum paint. The paper covering the rear face of the plaster board is thus rendered proof against the penetration of moisture, dampness, and the like. That portion of the paper 3 covering the front face of the plaster block 1, I treat with a compo- 110

sition to render the same fire resisting in character and at the same time render the front face of the plaster board porous in contradistinction to the rear face of the plaster board which is non-porous. In practice the moisture resisting and fire resisting paper is applied to the composition 1 and compressed thereon while the composition 2 is in a moist or wet condition. A detail view of the above described plaster board is shown in 10 Fig. 5.

In practice I prefer to assemble the above described moisture resisting and fire resisting plaster boards in the manner following, reference being had more particularly to Figs. 1 to 4. The reference numeral 5 designates the wall of a building. The reference numeral 6 designates a vertically disposed beam spaced apart from the wall 5, to provide an air space 7. The reference numeral 8 designates a horizontally arranged beam 20 supported at its ends by the wall 5. Those plaster boards 1 which are vertically disposed are secured to the beam 6 both at the floor and ceiling line by means of clips best seen in Fig. 3. Each clip is stamped from a single piece of sheet 25 metal and has struck out therefrom ears 9, 10, and 11 for engaging around a plaster board, see Fig. 1, U-shaped fashion. The body portion 12 of the clip is cut away at 13 to engage around the beam 6 and is provided with a wing 14 for 30 abutting against the rear of the beam 6, a struck-out part 15 being present for preventing the clip from slipping. Adjacent plaster boards 1 have fitted therebetween the clips best seen in Fig. 4. Each clip is formed from a single piece of sheet 35 metal and has struck out therefrom oppositely disposed fingers 16, 17, and 18 having serrated ends for engaging a plaster board. The body 19 of the clip is cut away at 20 to engage around beam 6 and is provided with a flanged part 21 40 to abut against the rear of beam 6, a finger 22 being provided to be bent over the rear flange of the beam 6 to hold the clip to place. Each plaster board 1 is apertured as at 23 and 24, see Fig. 2. Arranged for passage through the apertures 23 45 is a round rod 25, see Fig. 7. Each rod 25 has a hooked end 26 for engaging beyond an aperture 24 and the opposite end is provided with a prong 27 arranged to be driven into a plaster board, the rod serving to thus hold a pair of boards 50 in position. Arranged to engage apertures 24 of the plaster boards are flat members 28 the hooked end 29 of a member 28 engaging beyond an aperture 24 and the opposite or pointed end 30 being arranged to be driven into a plaster board. The rods 25 and members 28 are disposed 55 in parallelism and extend at an angle with respect

to the abutting ends or edges of the plaster boards. In Fig. 6, I have shown a structure in which each plaster board 1 vertical rods 31 which are concealed and upon the face of each board are exposed horizontal rods 32, the rods being formed of wire and being continuous. Free ends 33 of the wires 31 are left at certain places and at other places the wires 32 are cut so that companion plaster boards may be secured together by tying the wires as at 34.

Having placed the ceiling and wall plaster boards in position, plaster 28 is added which is shown in Fig. 1. All of the clips may be stamped from a single piece of metal and the clips shown in Fig. 3 may be apertured as at 29 so that nails may be driven therethrough for engagement with the plaster boards.

In the above described plaster board I first form a plaster board of plaster paris in the proportion of about 80% in bulb and add about 10% of powdered cork and about 10% of asbestos. When mixing the above ingredients with water I add about 20% of calcium chloride to render the finished plaster board impervious to water.

I am aware that the invention may be embodied in other specific forms without departing from the spirit or essential attributes thereof, and I therefore desire the present embodiment to be considered in all respects as illustrative and not restrictive, reference being had to the appended claim rather than to the foregoing description to indicate the scope of the invention.

What I claim is:

A lathing structure for plaster walls comprising supporting studs, panels extended across the front faces of said studs and secured with respect thereto, means including clips for holding adjacent panels together, each panel being reinforced by means of a continuous wire extending both longitudinally and laterally of said panel, whereby the longitudinally extended portion of said wire is exposed and the laterally extended portion of said wire is concealed, the arrangement of said wire being such that the exposed portions of said wire when severed may have the cut ends thereof twisted with respect to the cut ends of an exposed portion of said wire of a companion plaster board, each of said panels being apertured in spaced and staggered relation, and a pair of tie rods arranged in parallelism, which tie rods are arranged at an inclination, each tie rod passing from a panel back through an aperture and across the front faces of adjacent panels for coupling said adjacent panels together independently of said clips.

FREDERICK M. VENZIE,
